UNITED STATES PATENT OFFICE.

GEORGE W. WILMOT, OF HAZLETON, PENNSYLVANIA, ASSIGNOR TO WILMOT ENGINEERING COMPANY, OF HAZLETON, PENNSYLVANIA, A CORPORATION OF PENNSYLVANIA.

COAL JIG.

Application filed December 23, 1921. Serial No. 524,342.

To all whom it may concern:

Be it known that I, GEORGE W. WILMOT, a citizen of the United States, and a resident of Hazleton, in the county of Luzerne 5 and State of Pennsylvania, have invented an Improvement in Coal Jigs, of which the following is a specification.

My invention relates to jigs for washing and separating coal from slate and other 10 material which it is desired to eliminate, and it has for its principal object to provide an improved means whereby the separation of the coal and slate may be effected more efficiently and more expeditiously than 15 heretofore, as far as I am aware, has been practical.

Somewhat more specifically stated my invention comprises an improvement in the means for preventing return or reverse 20 flow of the water through the openings in the bottom of the jig pan of a jig during the vibration thereof in operation.

My invention comprehends the construction and arrangement of parts as herein- 25 after more fully described, particularly pointed out in the claims and as illustrated in the drawing, in which one form of embodiment of the invention is shown. However, it will be understood that various 30 changes in the details of construction may be made within the scope of the claims without departing from my invention.

In the drawing:

Fig. 1 is a view in longitudinal sectional 35 elevation of a coal jig apparatus showing a jig pan provided with my invention, the said view being taken along a line corresponding to the line 1—1 of Fig. 2;

Fig. 2 is a top plan view of a portion of a 40 jig pan and of a portion of the device attached thereto to constitute my invention, a portion of the said jig pan being broken away in order to show more clearly the construction of the said device;

Fig. 3 is a longitudinal sectional view of 45 the said device which is adapted to be attached to the under side of the jig pan;

Fig. 4 is a longitudinal sectional view of 50 the said device with one of the parts thereof in a different position from what it is shown in Fig. 3;

Fig. 5 is an enlarged longitudinal sec- 55 tional view of a portion of the bottom of

the said device showing more clearly the detailed construction thereof; and 55

Fig. 6 is a top plan view of a portion of the bottom of the said device.

Referring to the drawings: 1 designates a jig tank partially filled with water as shown and which is supported upon the frame structure 2. The jig pan is shown at 3 and is supported by means of supporting bars, one of which is shown at 4. There are two of these bars employed in constructions of the character of that illustrated. 60 They are supported at their upper ends upon eccentrics 5 secured or formed upon a rotatable shaft 6. The lower ends of the supporting bars 4 are held and guided in guides 7 in known manner. Upon rotation of the 70 shaft 6 the supporting bars 4 are reciprocated or moved up and down and are at the same time rocked or oscillated about their lower end portions as centers causing corresponding vibratory and oscillating 75 movements of the jig pan 3. The bottom 9 of the latter is provided with holes of sizes which vary with the sizes of coal which are to be treated or "jigged." The coal with any admixture of slate and other foreign 80 matters, such as stone, which may be present is delivered to the jig pan 3 from a trough or chute 11 in the usual known manner, and the washed coal is delivered from the pan through a discharge chute or mouth 85 12 while the heavier material, such as slate, stone, etc., is discharged through the passageway 15 and over a baffle 16.

Heretofore, as far as I am aware, no means has been provided for accelerating the flow 90 of water through the oscillatory and vibratory jig pans in structures of the character above described. By my invention I am enabled to effect an acceleration of the flow of water through the jig pans to thereby 95 effect not only a more efficient but a more rapid separation of the coal from slate and other foreign substances, such as stone.

For this purpose I have provided a supplemental pan-like structure 20 having a bottom 21 with perforations or holes 22 therein. These holes are arranged in rows, as shown, and those in each row are adapted to be opened and closed by means of a feather valve 23, there being as many feather 100 valves as there are rows. These feather

valves respectively consist of thin relatively long sheets of suitable material, such as rubber, wood, metal, etc., and they are movably supported upon short studs or posts 24 which are secured to the portions of the bottom of the said pan-like structure intermediate adjoining openings. These posts extend through holes in the feather valve strips and are provided with cotter pins 25 at their upper ends for retaining the feather valve strips thereon. The upper edge portions of the opposite sides 26 of the pan-like structure 20 are situated on the outside of and overlap the lower edge portions of the opposite sides of the jig pan 3. The inner surfaces of the upper edge portions of the said sides 26 should contact or practically contact with the overlapped side portions of the jig pan.

20 It has been found that the flow of water through the jig pan may be further accelerated and the efficiency of operation increased by providing means which prevents or which tends to prevent lateral or outward flow of the water from underneath the structure 20 upon the descending movements thereof when the apparatus is in operation. The means provided by me for that purpose comprises what may be described as a skirt which surrounds and projects a distance below the outer edges of the bottom of the supplemental structure 20 or an equivalent thereof. In the construction as shown the said skirt comprises flange-like side and end portions 20* which flare slightly outwardly and which are secured to the sides and ends of the said structure 20. The said skirt, however, may be supported in any other suitable manner, the only essential requirement being that it shall extend around the bottom of the said supplemental structure and extend a distance below the plane of said bottom so that upon downward movements of the jig pan and the said supplemental structure the said skirt will tend to prevent lateral or outward flow of water from underneath the bottom of the said structure thereby tending to cause it to flow upwardly through the perforations or holes 22 in the bottom thereof.

25 The upper edge portion of the end 30 of the pan-like member 20 is slotted or notched as indicated at 31 and is provided with outwardly extending pairs of spaced lugs or 35 projections 32. The lugs of the respective pairs are adapted to occupy positions upon opposite sides of lugs 33 projecting outwardly from the lower edge portion of the adjacent end of the jig pan 3. The lugs 32 and 33 are adapted to be pivotally connected together by means of the pivot bolts 34. The upper edge of the opposite end 40 of the device 20 is adapted to contact with the lower side of the bottom 9 of the jig pan 65 as shown in Fig. 3. The said end is pro-

vided with outwardly extending lugs 41 arranged in pairs as shown. Lugs, not shown, which project downwardly from the bottom 9 of the jig pan 3 extend between the respective pairs of lugs 41 and are secured thereto by means of rods 42. Only one of these rods is shown. Both pairs of lugs 32 and 41 are situated near the opposite ends of the end walls 30 and 40 of the pan-like device 20.

70 It will be understood that the device 20 may be secured to the underside of the jig pan 3 in any manner other than shown as may be preferred or desired and that my invention is not limited to the particular way in which the said device 20 is shown as being secured or attached to the said jig pan. One advantage of securing the said device 20 to the jig pan as shown is that by removing the rods 42 the said device may be dropped down so as to permit access to the valve structures provided therein so as to make any repairs or alterations thereof which may be found to be desirable or necessary.

75 In the operation of the device and as already indicated the coal, with which slate and other foreign matter such as stone may be admixed, is discharged into the jig pan from the trough or chute 11. The jig pan together with the device 20 is subjected to a combined reciprocating and oscillating movement or vibration. Such movement causes the water to flow through the openings 10, the sizes of which may vary with the sizes of coal treated. By reason of the presence of the device 20 provided with the valve controlled openings 22 therein the flow of the water through the jig pan is accelerated to such an extent that a structure of this character may be satisfactorily and efficiently employed in the washing and separating of slate and stone from the smaller sizes of coal; that is, sizes from one quarter of an inch in diameter down to the smallest sizes which are in general commercial use.

80 It will be apparent that as the jig pan and the device 20 descend the feather valves 23 will be moved upwardly upon their supporting studs or posts 24 so as to permit water to flow through the openings 22 and thence through the openings 10. Upon movement of the jig pan and device 20 in the opposite direction or upwardly the feather valves 23 descend upon the studs or posts 24 so as to close the openings 22 and prevent water from flowing in reverse direction or downwardly through the openings 10. The water flows up through the openings 22 and 10, thence to the right, downwardly and again up through the said openings. It has been found in actual practice that the operation of the device is such as to lower the water a considerable distance in the space between the left hand end walls 130

of the jig pan 3 and of the device 20 and the adjacent opposing end wall of the tank 1. By reason of the presence of the device 20 with the valve controlled openings 22 I 5 am, as already described, enabled to cause an accelerated movement or flow of the water through the jig pan whereby a reciprocating and oscillating jig pan of the character of that shown may be employed effi- 10 ciently in the treating of the smaller sizes of coal, and as already indicated, the invention may be employed to advantage with the larger sizes of coal or other similar or equivalent material.

15 Having thus described my invention, what I claim and desire to secure by Letters Patent is:

1. In a coal jig comprising a tank having water therein, the combination of a jig pan 20 partially submerged within said water, means for causing vibratory and rocking movement of the said jig pan, a receptacle of separate structure situated underneath the said jig pan and detachably carried 25 thereby, the upper side of said receptacle being closed by the bottom of the said jig pan, and the said receptacle being provided with valve controlled openings in the bottom thereof, substantially as described.

30 2. In a coal jig comprising a tank having water therein, the combination of a jig pan, a pan-like separate structure situated underneath the said jig pan, means for detachably securing the said pan-like structure to the said jig pan, the said pan-like structure inclosing a chamber underneath the bottom of the said jig pan and the bottom of the said pan-like structure being provided with a plurality of openings and valves for opening and closing the said openings, the said valves being actuated by the movements of the said jig pan and pan-like structure within the water of the said tank.

35 3. In a jig comprising a tank adapted to contain water, the combination of a jig pan, means for effecting vibratory and rocking movements of the said pan, a pan-like structure underneath the said jig pan and having upper edge portions thereof secured to the said jig pan whereby the said pan-like structure partakes of the movements of the said jig pan, and the bottom of the said pan-like structure being provided with a

plurality of openings therein arranged in rows, and a plurality of disconnected strips 55 independently and movably retained in position over the said openings to control the passage of water therethrough during the vibratory and oscillatory movements of the said jig pan and pan-like structure. 60

4. In a coal jig comprising a tank adapted to contain water, the combination of a jig pan, means for effecting vibration thereof, a receptacle situated underneath the said jig pan and forming a chamber underneath the bottom thereof, the bottom of said receptacle being provided with a plurality of valve controlled openings for controlling the flow of water from the tank into the said chamber of said receptacle and into the said jig 70 pan, and means for detachably connecting the said receptacle to the said jig pan.

5. In combination, a jig pan which is adapted to be vibrated, the said jig pan having openings through the bottom thereof, a pan-like member situated underneath the bottom of the said jig pan and also having holes through its bottom, said pan-like member being pivoted to one end portion of the said jig pan, the other end of said 75 pan-like member having detachable connection with the said jig pan, and valves within the said pan-like member for opening and closing the holes through the bottom thereof.

6. In a coal jig comprising a tank having water therein, the combination of a jig pan partially submerged within said water, the bottom of said jig pan having perforations extending therethrough, a supplemental 90 structure supported upon said jig pan and situated underneath the same, the said supplemental structure being provided with valve controlled openings which are adapted to be opened upon the descending movements of the said jig pan and are adapted to close upon the ascending movements thereof, and means carried by said supplemental structure tending to prevent lateral flow of the water from underneath the same 95 upon the descending movements thereof.

In testimony that I claim the foregoing as my invention, I have hereunto signed my name this 17th day of Dec., A. D. 1921.

GEORGE W. WILMOT.
